(57) **CLAIM**

The ornamental design for an emergency radio, as shown and described.

DESCRIPTION

FIG. 1 is a perspective view of an emergency radio in accordance with the present invention;

FIG. 2 is a front elevation view of the motion sensor of FIG. 1;

FIG. 3 is a rear elevation view of the motion sensor of FIG. 1;

FIG. 4 is a left side elevation view of the motion sensor of FIG. 1;

FIG. 5 is a right side elevation view of the motion sensor of FIG. 1;

FIG. 6 is a top plan view of the motion sensor of FIG. 1; and, FIG. 7 is a bottom plan view of the motion sensor of FIG. 1.

The broken lines, which define the boundary of the claimed design, form no part thereof.
